SUCTION NOZZLE FOR VENTILATING WATER CLOSETS

Manuel J. Mendoza, Hallandale, Fla.

Application March 28, 1958, Serial No. 50,222

Term of patent 14 years

(Cl. D9—2)

FIG. 1

FIG. 2

FIG. 3

FIG. 4

FIG. 5

FIG. 6

FIG. 7

Figure 1 is a top plan view of a suction nozzle for ventilating water closets, showing my new design.

Figure 2 is a bottom plan view thereof.

Figures 3 and 4 are rear and front elevational views, respectively.

Figures 5 and 6 are side elevational views thereof.

Figure 7 is a longitudinal sectional view taken along the line 7—7 of Figure 1.

I claim:

The ornamental design for a suction nozzle for ventilating water closets, substantially as shown.
